TRIGGER MECHANISM

Leslie A. Skinner, United States Army,
Aberdeen Proving Ground, Md.

Application June 22, 1933, Serial No. 677,076

13 Claims. (Cl. 42—69)

(Granted under the act of March 3, 1883, as
amended April 30, 1928; 370 O. G. 757)

The invention described herein may be manufactured and used by or for the Government for governmental purposes, without the payment to me of any royalty thereon.

5 This invention relates to a trigger mechanism for firearms.

The purpose of this invention is to provide a trigger which cannot be definitely engaged by the finger but which may be actuated by a perfectly natural flexion of the finger. The end to be attained is the elimination of jerking, flinching, and the necessity for practicing the "trigger squeeze."

10 The improved trigger consists broadly of a pair of spaced members, one of which is a sear-actuating member, mounted to yield upon passage between them of the finger of an operator.

To these and other ends, the invention consists in the construction, arrangement and combination of elements described hereinafter and pointed out in the claims forming a part of this specification.

15 A practical embodiment of the invention is illustrated in the accompanying drawing, where-
20 in:

Fig. 1 is a view partly in side elevation and partly in section showing the improved trigger mechanism.

Fig. 2 is a sectional view on the line 2—2 of
25 Fig. 1.

Fig. 3 is a view similar to Fig. 1 of a modified form of trigger.

Referring to Fig. 1 there is shown a rifle of the Springfield type having the conventional 30 firing pin 5, sear 6, and sear spring 7 and a modified sear lever 8 and trigger guard 9.

The trigger mechanism consists of a pair of spaced movable members, specifically balls 10 and 11, between which the finger is moved.

40 The upper ball 10 is carried in a socket 12 secured to the upper part of the guard 9 as by screws 13 and extends into the receiver of the gun. A plunger having a head 14 engaging the ball and a stem 15 projecting through the base 16 of the socket to engage the sear lever 8, is actuated by a spring 17 which normally tends to hold the ball against the lip 18 of the socket and to release pressure of the stem on the sear lever.

45 The lower ball 11 is carried in a socket 19 that is adjustably mounted in the bow of the trigger guard so that the distance between the two balls may be regulated to accommodate the finger of the operator. One method of obtaining this adjustable mounting is to provide the socket with 50 threads 20 whereby it is engageable by a nut 21.

The nut is preferably inserted from the inside of the guard into an aperture 22 in the bow of the guard and includes a collar 23 adapted to engage the inner side of the bow. A ring 24 secured to the nut as by screws 25 is adapted to engage the outer side of the bow. The nut is thus free to rotate but is constrained against displacement relative to the guard.

55 The ball 11 is held against the lip 26 of the socket by means of a spring 27. The plug 28 threaded in the socket forms a seat for the spring 27 and enables the tension of the spring to be adjusted. The spring 27 is approximately equal in strength to the springs 7 and 17. When desired the sear lever spring 7 may be used solely 60 to hold the ball 10 against the lip of its socket, and the spring 17 will be omitted. A clear illustration of such omission is shown in Fig. 3 in which the ball is designated 10a, the sear lever 8a, and sear lever spring 7a. The actuating mechanism will 65 of course depend on the construction of the lock of the firearm.

The socket 19 includes a plate 29 which forms a rest and guide for the finger of the operator and has a recess or slot 30 in its rear end for receiving 70 a rib 31 on the trigger guard. This provision constrains the socket to axial displacement when the nut is rotated.

75 In operation, the finger of the operator is inserted through the trigger guard in the usual manner and engages the forward sides of the balls 10 and 11. Upon flexing the finger, the balls are caused to revolve and yield to the passage of the finger. The consequent displacement of the upper ball 10 acts either directly or through interposed motion transmitting members, to disengage the sear from the firing pin. The finger cannot definitely engage the balls as it does the usual trigger. As a result muscular tension will be eased and there will not be an impulse to jerk 80 and flinch and thereby cause the muzzle of the firearm to be deflected from its intended line. In conducting training in marksmanship it will not be necessary to have the student practice the "trigger squeeze" because the only requirement is 85 a perfectly natural movement of the finger without the conscious opposition of the conventional trigger.

90 While the invention has been illustrated as employing freely revolving balls it is to be clearly understood that one or both of the balls may be replaced by a resilient member as indicated at 95 32 in Fig. 3.

I claim:

1. In a trigger mechanism for firearms, a sup- 100

105 55 threads 20 whereby it is engageable by a nut 21.

110

port, a pair of spaced balls carried by the support and mounted to yield upon passage of the finger of an operator, said balls mounted for displacement and freely revolvable, a sear adapted to be moved through one of the balls, a sear spring, a spring resiliently supporting the other ball and having approximately the same strength as the sear spring.

2. In a trigger mechanism for firearms, a support, a pair of spaced balls carried by the support and mounted to yield in opposite directions upon passage between them of the finger of an operator, said balls mounted for displacement, a sear adapted to be moved through one of the balls, a sear spring, a spring resiliently supporting the other ball and having approximately the same strength as the sear spring.

3. In a trigger mechanism for firearms, a support, a pair of spaced balls carried by the support and mounted to yield upon passage of the finger of an operator, said balls mounted for displacement and freely revolvable, a sear adapted to be moved through one of the balls, a sear spring, a spring resiliently supporting the other ball.

4. In a trigger mechanism for firearms, a support, a pair of spaced balls carried by the support and mounted to yield in opposite directions upon passage between them of the fingers of an operator, said balls mounted for displacement, a sear adapted to be moved through one of the balls, a sear spring, a spring resiliently supporting the other ball.

5. In a trigger mechanism for firearms, a support, a pair of spaced balls carried by the support and mounted to yield upon passage between them of the finger of an operator, said balls being freely revolvable, and a firing member associated with only one of said balls.

6. In a trigger mechanism for firearms, a support, a pair of spaced balls carried by the support and mounted to yield upon passage between them of the finger of an operator, and a firing member associated with only one of said balls.

7. In a trigger mechanism for firearms, a support, a pair of spaced members carried by the support and mounted to yield upon passage between them of the finger of an operator, resilient means of approximately equal strength for holding the members in normal finger-engaging position, and means for displacing one of the

members and its resilient means to adjust the spacing between the members.

8. In a trigger mechanism for firearms, a support, a pair of spaced members carried by the support and mounted to yield upon passage between them of the finger of an operator, resilient means for holding the members in normal finger-engaging position, and means for displacing one of the members and its resilient means to adjust the spacing between the members.

9. In a trigger mechanism for firearms, a support, a pair of spaced members carried by the support and mounted to yield upon passage between them of the fingers of an operator, resilient means for holding the members in normal finger-engaging position, and means whereby the spacing between the members may be adjusted.

10. In a trigger mechanism for firearms, a support, a pair of spaced members carried by the support and mounted to yield upon passage between them of the finger of an operator, resilient means for holding the members in normal finger-engaging position, and a firing member associated with only one of said yielding members.

11. In a trigger mechanism for firearms, a support, a pair of spaced members carried by the support and mounted to yield upon passage between them of the finger of an operator, and a firing member associated with only one of said yielding members.

12. In a trigger mechanism for firearms, a support, a nut carried by the support and restricted to rotational movement, a socket threadedly carried by the nut, and a finger rest and guide on the socket and engageable with the support whereby it is restricted to axial displacement, a ball carried by the socket, and a sear actuating member spaced from the ball and mounted to yield upon passage of the finger of an operator.

13. In a trigger mechanism for firearms, a support, a ball carried by the support and mounted to yield when engaged by the upper portion of the finger of an operator, and a member spaced from the ball and mounted to yield when engaged by the lower portion of the finger of the operator.
